(57) **CLAIM**

The ornamental design for a scooter with inflatable base, as shown and described.

DESCRIPTION

FIG. 1 is a top perspective view of a scooter with inflatable base;

FIG. 2 is a top plan view of the scooter with inflatable base of FIG. 1;

FIG. 3 is a bottom view of the scooter with inflatable base of FIG. 1;

FIG. 4 is a first end view of the scooter with inflatable base of FIG. 1;

FIG. 5 is a second end view of the scooter with inflatable base of FIG. 1;

FIG. 6 is a first side view of the scooter with inflatable base of FIG. 1; and,

FIG. 7 is a second side view of the scooter with inflatable base of FIG. 1.

The broken lines shown are included for the purpose of illustrating the unclaimed portions of the scooter and form no part of the claimed design.

1 Claim, 5 Drawing Sheets
